UNITED STATES PATENT OFFICE.

EDWARD O. ELLIOTT, OF PHILADELPHIA, PENNSYLVANIA, ASSIGNOR TO THE BALDWIN LOCOMOTIVE WORKS, OF PHILADELPHIA, PENNSYLVANIA, A CORPORATION OF PENNSYLVANIA.

THREE-CYLINDER LOCOMOTIVE.

Application filed June 7, 1924. Serial No. 718,578.

To all whom it may concern:

Be it known that I, EDWARD O. ELLIOTT, a citizen of the United States, residing in Philadelphia, Pennsylvania, have invented 5 certain Improvements in Three-Cylinder Locomotives, of which the following is a specification.

My invention relates to certain improvements in three cylinder locomotives, in 10 which two cylinders are located outside of the main frame of the locomotive, and the third cylinder is located at the center of the locomotive between the frames.

The application is a companion to an application filed by me on the 31st day of 15 May, 1924, Serial No. 716,981.

One object of the present invention is to locate the central cylinder so that the distance between the rear end of the cylinder 20 and the crank axle is of sufficient length for the proper movement of the connecting rod and the cross head.

A further object of the invention is to design the steam inlet passages so that the 25 valve chest of the third, or intermediate, cylinder will receive steam direct from the steam pipe leading to the valve chest of one of the side cylinders.

In the accompanying drawings: Fig. 1 30 is an end view of the saddle and cylinder castings of a three cylinder locomotive, the frame of the locomotive being shown in section; Fig. 2 is a plan view; and Fig. 3 is a side view.

Referring to the drawings, 1, 1 are the 35 longitudinal side frames of a locomotive. 2 is a saddle, which rests on said frames and is bolted securely thereto. The sides of this saddle extend beyond said frames, as shown 40 clearly in Fig. 1.

The side cylinder castings 3 are secured to the sides of the saddle by bolts, or other fastenings, both parts being provided with flanges for the passage of the bolts. This 45 construction is fully set forth and claimed in the application hereinbefore alluded to.

4, 4 designate the side cylinders. 5, 5 50 designate the valve chests for said cylinders, which, in the present instance, are cast integral with the cylinders. 6 designates the central, or third, cylinder. Located on the central longitudinal line of the saddle, and at one side of the cylinder, is its valve chest 7.

It will be noticed, on referring to Fig. 3, 55 that the central cylinder 6 is arranged at an angle in respect to the cylinders 4. In order to increase the length between the back end of the cylinder and its crank axle, the cylinder projects beyond the forward 60 end of the saddle, as shown clearly in Figs. 2 and 3, and the back end of the cylinder terminates some distance within the saddle, as shown by dotted lines in Fig. 3. The cylinder and its valve chest, in the present 65 instance, are integral parts of the saddle.

At the upper end of the saddle is a curved flange 8 to which the smoke box is secured. A portion of the saddle extends into the 70 smoke-box, as shown.

The live steam pipe 9 communicates with the right hand valve chest 5 of the right hand cylinder, and the live steam pipe 10 communicates with the valve chest 5 of the left hand side cylinder. 75

An S-shaped pipe 11 is connected to the pipe 10 and communicates with the valve chest 7 of the central cylinder 6 so that the steam from the pipe 10 flows not only to the valve chest 5, but also to the valve 80 chest 7.

Extending around the major portion of the cylinder 6, and located within the saddle, is an exhaust passage 12, which communicates with the exhaust passage 13 in 85 the left hand cylinder casting 3, and with the exhaust passage 14 in the right hand cylinder casting 3.

The exhaust passages from the intermediate valve chest 7 also communicate with 90 the main exhaust passage 12. The exhaust passage extends to the nozzle base 16 within the smoke-box and passes through the nozzle that is mounted on this base, but which is not shown in the drawings. 95

The exhaust passages in the cylinder castings communicate with each end of each valve chest, as shown by dotted lines in Fig. 2.

The exhaust passage 12 also communicates 100 with each end of the valve chest 7.

By the construction hereinbefore described, an engine can be built without materially increasing the wheel base, as the location of the central cylinder, in the manner shown, provides sufficient space for the movement of the cross-head and its connecting rod. The live steam is directed 105

through a short pipe from the main steam supply pipe to the chest of the third cylinder.

I claim:

- 5 1. The combination in a three cylinder locomotive, of a longitudinal frame of the locomotive; a saddle mounted on the frame; a cylinder cast integral with the saddle, the forward end of the cylinder projecting beyond the forward end of the saddle; and side cylinder structures secured to the saddle.
- 10 2. The combination in a three cylinder locomotive, of the main longitudinal frames of the locomotive; a saddle mounted on the frames; side cylinder structures secured at each side of the saddle; and a central third cylinder cast integral with the saddle and arranged at an angle in respect to the longitudinal line of the locomotive, said cylinder projecting at its forward end beyond the forward end of the saddle and terminating within the saddle.
- 15 3. The combination in a three cylinder

locomotive, of a frame; a saddle mounted thereon; a central cylinder and its valve chest cast within the saddle, the valve chest being at one side of said cylinder; side cylinder castings, each having a valve chest, said castings being secured to the sides of the saddle; outside steam pipes leading directly to the valve chests of the side cylinder castings; an outside pipe forming a connection between one of said steam pipes and the valve chest of the central cylinder; and exhaust passages formed in the saddle.

20 4. The combination in a three cylinder locomotive, of the main frames of the locomotive; a cylinder saddle mounted on the main frames; a central cylinder and its valve chest cast integral with the saddle, said cylinder projecting beyond the saddle at the forward end; side cylinder castings, each having a valve chest; steam pipes leading to said valve chests; and an S-shaped pipe leading from one of the steam pipes to the valve chest of the central cylinder.

EDWARD O. ELLIOTT.
